[57] CLAIM

The ornamental design for a ladle for aluminum die casting or the like, substantially as shown and described.

DESCRIPTION

FIG. 1 is an isometric view of a ladle for aluminum die casting or the like showing our new design;
FIG. 2 is a front elevational view thereof;
FIG. 3 is a top plan view thereof;
FIG. 4 is a side elevational view thereof;
FIG. 5 is a rear elevational view thereof; and
FIG. 6 is a bottom plan view thereof.

FIG. 2

FIG. 1

FIG. 3

FIG. 4

FIG. 5

FIG. 6
